UNITED STATES PATENT OFFICE.

SAMUEL C. McKEOWN, OF EAST ORANGE, NEW JERSEY, ASSIGNOR TO SPLITDORF ELECTRICAL COMPANY, OF NEWARK, NEW JERSEY.

BRUSH-HOLDER.

1,323,888.

Specification of Letters Patent.

Patented Dec. 2, 1919.

Original application filed September 25, 1917, Serial No. 193,119. Divided and this application filed May 1, 1919. Serial No. 294,067.

To all whom it may concern:

Be it known that I, SAMUEL C. McKEOWN, a citizen of the United States, and resident of East Orange, in the county of Essex and 5 State of New Jersey, have invented certain new and useful Improvements in Brush-Holders, of which the following is a specification.

My invention relates to brush holders for 10 electrical apparatus used in connection with ignition systems for internal combustion engines.

My invention is particularly adapted for use in connection with a magneto used for 15 the purpose of producing and distributing sparking current to the sparking devices located in the various engine cylinders. Magnetos used for this purpose usually have a distributor block which carries the contacts to which the spark plug wires are attached; at the same time the block acts as a housing for the distributing finger which serves as a medium for conducting current from the secondary of the high tension coil 20 to the various distributor points by way of a distributor brush carried by the distributing disk or finger.

In order that the brush carried by the rotating distributing finger may be kept in its 30 proper working position a spring of some kind is utilized to continually force the brush outward from its retainer and when the block is removed for any purpose whatsoever, the distributor brush will pop out of its retainer unless restrained by some means.

One of the objects of my invention is to provide a brush holder which has a restraining means suitable for retaining the brush in the holder when the distributor block has 40 been removed.

Another object of my invention is to provide a retainer which will serve as a means for withdrawing the brush from the holder itself whereby damage to the brush and its 45 operating spring is reduced to a minimum. That is to say, the retainer acts as a protector for the brush and spring.

These and other objects will be apparent to one skilled in the art after a study of 50 this specification in connection with the drawing, in which—

Figure 1 is a fragmentary sectional view of a portion of a distributor block with the

distributing finger and means for driving the same.

Fig. 2 shows the brush holder and retainer partly withdrawn from the holder.

Referring now particularly to the details, 1 is a portion of the end plate of a magneto within which is mounted a ball bearing 2 60 that carries a distributor gear 3. Gear 3 is driven in the usual way from the pinion on the armature or rotor of the magneto but since this is all old and well understood and forms no part of my invention further 65 description of this part of the magneto does not appear necessary. The sleeve 4 to which the gear 3 is attached carries an insulating finger 5 having a stem 6 in which is molded a metal insert 7, which carries a brush 8 70 for purpose of collecting the high tension current from any suitable connecting device. Preferably molded integrally with the finger 5 is a brush holder 9 adapted to carry a retainer 10. The retainer 10 is indented 75 along one side at 11 which indentation serves as a guide for the brush 12 which has a groove 13 to coact with the guide 11. The brush holder 9 also has an indentation 14 that matches with indentation 11 of the retainer so that the retainer 10 is guided in 80 the brush holder 9. The bottom part of the retainer 10 has an indentation 16 which acts to form a seat for the spring 18, the upper end of which is held in operative relationship with the brush 12 by a projection 15.

The spring 18 serves to hold the brush 12 in a position such that the shoulder 17 is always engaged by the hook 24 formed on one side of the retainer 10. This side has a 85 slight set at 25 so that when the retainer is withdrawn from the holder the hook 24 will spring outward as shown in Fig. 2 whereby the brush 12 may be readily withdrawn from the retainer. By this construction the brush, retainer and holder have 90 grooves and guideways similar to that shown in my co-pending application S. N. 193,119, filed September 25, 1917, of which this application is a division.

As shown in Fig. 1 the spring 18 holds the brush 12 in normal working position, in which the end of the brush 12 runs against the pathway of the distributor block 19 in which are molded a number of inserts 20 105 corresponding to the number of engine cyl-

inders required to be served by the magneto. The wires running from the distributor block 19 to the engine cylinders are connected to the contacts 20 by means of the 5 openings 21 and screws passing through the threaded holes 22. The distributor block 19, as shown, has other contact points 23 but since these form no part of my present invention they are not further described 10 herein.

It will be understood that numerous changes may be made in the details of my invention without departing from the spirit 15 of my invention and the scope of the appended claims.

Having thus described my invention what I claim is:—

1. In a device of the class described, a brush having a shouldered portion and a 20 channel therein, a retainer for the brush and having a guide adapted to coöperate with the channel, a holder for the retainer and having a guide therefor, a spring supported

in the retainer for moving the brush outward as the same wears, said retainer having 25 a hook-shaped member adapted to be brought into the path of movement of the shouldered portion of the brush to limit its outward movement, when the retainer is inserted all the way into the holder as described.

2. In a device of the class described, a brush having a shouldered portion and a channel therein, a retainer for the brush and having a guide adapted to coöperate with the channel, a holder for the retainer and having a guide therefor, a spring supported 35 in the retainer for moving the brush outward as the same wears, said retainer having a resilient portion terminating in a hook 40 adapted to engage, when the retainer is in working position in the holder, the shouldered portion of the brush to limit its outward movement, as described.

In witness whereof I affix my signature.
SAMUEL C. McKEOWN.
